UNITED STATES PATENT OFFICE.

JOSEPH ANTHONY SEGALINI, OF NEW YORK, N. Y.

WINDOW FASTENER.

Application filed May 24, 1926. Serial No. 111,354.

The present invention is concerned with the provision of a window fastening device which will serve the double purpose of preventing rattling of a pair of sliding sashes, and of selectively locking the sashes against relative sliding movement in one direction. With the device of the present invention, one or the other, or both sashes may be partially opened and the fastener will effectively prevent forcible movement of the sashes to further opened position. In other words, the lower sash may be slightly raised, or the upper sash slightly lowered, and the fastener will prevent the entrance of an intruder.

A further object of the invention is to provide a sash fastener of the character noted above, which may be conveniently locked in inoperative position, which will never interfere with the sliding movement of the two sashes to closed position, and which may be expeditiously installed on any ordinary type of sliding sash without requiring the services of a mechanic.

Further objects of the invention are to provide a sash fastener of simple, practical construction, which will be rugged, durable and efficient in use, which is well suited to the requirements of economical manufacture, and which may be conveniently manipulated to shift the same into or out of operative position.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a fragmentary perspective view showing a portion of a window frame with a pair of sliding sashes mounted therein, and one of my improved window fasteners in position.

Fig. 2 is a transverse sectional detail view through the upper portion of one sash and the lower portion of the other sash, the window fastener being shown in section and in its inoperative position.

Fig. 3 is a view similar to Fig. 2, but showing the fastener in operative position to block relative sliding movement of the two sashes.

Fig. 4 is a top plan view of the fastener. In the drawings I have used the reference character 10 to designate a window frame within which are mounted an upper sliding sash 11 and a lower sliding sash 12. The window fastener of the present invention is mounted upon the top of the lower sliding sash at one or both sides thereof in convenient position for coaction with the side

rails of the upper sash.

The fastener is preferably carried or mounted upon a base plate 13 secured to the top of the sash 12 in any convenient manner as by the use of screws 14. The base plate may be provided at one end with a flange 15 which overlies the edge of the top rail of the sash 12. Intermediate its ends the base plate is preferably integral with a pair of upstanding ears 16 mounting a pivot pin 17 between them.

An angular lever 18 is formed with side flanges 19, apertured for the reception of the pivot pin 17. One end 20 of the lever 18 constitutes a wedge which blocks the sliding movement of the two sashes, and the other end 21 of the lever terminates in a tail piece 22 which constitutes a handle for rocking the lever on the pin 17.

Encircling the pin 17 is a coiled torsional spring 23, one end 24 of which bears against the under face of the portion 21 of the lever and is retained against lateral movement by one of the side flanges 19. The other end of the spring bears against the base plate 13, and is retained against lateral movement by one of a pair of ears 25 struck upwardly from the side edges of the base plate.

The tendency of the spring 23 is to forcibly urge the wedging end 20 of the lever 18 into engagement with the upper sash 11. With the wedge spring pressed into engagement with the upper sash, it will be seen that sliding movement of this sash in a downward direction is effectively blocked. The greater the pressure which is applied in an attempt to effect such relative movement, the more firmly the wedging member 20 is jammed into the sash. Obviously this wedging result will take place whether the sashes are completely closed as shown in Fig. 1, or whether either or both of the two sashes are partially opened.

Some means must be provided for locking the lever 18 in inoperative position in order to permit free sliding movement of the two

sashes. One efficient means for accomplishing this purpose has been illustrated, which consists of the use of a swinging bail 30, the ends 31 of which pivot freely in the flanges 5 19, and the intermediate portion 32 of which is adapted to rest on the base plate 13. When the finger piece or tail piece 22 of the lever 18 is depressed. The lever will be rocked against the action of its spring from 10 the position of Fig. 3 to the position of Fig. 2, and incidental to such rocking movement, the bail 30 will be shifted to vertical position. Upon release of the finger piece 22 the bail 30 will act automatically as a prop or 15 blocking strut as seen in Fig. 2 to retain the wedge 20 out of engagement with the sash 11.

20 The ears 25 are preferably formed of spring material and may act as a supplemental means for locking the lever 18 in inoperative position. If the finger piece 22 is depressed as far as possible, the flanges 19 will wedge between the ears 25, and the lever 18 will be locked in inoperative position 25 with the bail 30 out of contact with the plate 13.

30 It will be apparent that the fastener when in use will prevent undue vibration of the two sashes, particularly if a fastener is used at each side of the window. The function of the device as a lock has already been set forth.

35 Obviously various changes and alterations might be made in the general form and arrangement of parts described without departing from the invention. Hence I do not wish to limit myself to the details set forth, but shall consider myself at liberty

to make such changes and alterations as fairly fall within the spirit and scope of the 40 appended claims.

I claim:

1. In a window fastener, a base plate, an angular lever pivoted intermediate its ends above the base plate, a spring urging the 45 lever in one direction about its fulcrum, and a swinging bail carried by the lever engageable with the base plate and acting as a prop to limit the rocking movement of the lever under the influence of the spring. 50

2. A window fastener including a base plate, a pair of ears rising from the base plate, an angular lever including depending side flanges pivoted between the ears, a coiled torsional spring encircling the pivot 55 pin and urging the lever in one direction, a tail piece on the lever for manually rocking the same against the action of the spring, and a second pair of ears between which the flanges are adapted to be wedged to lock the 60 lever against movement under the impetus of the spring.

3. A window fastener including a base plate, a pair of ears rising from the base plate, an angular lever including depending 65 side flanges pivoted between the ears, a coiled torsional spring encircling the pivot pin and urging the lever in one direction, a tail piece on the lever for manually rocking the same against the action of the spring, 70 and a swinging bail mounted in the flanges and engageable with the base plate, operable to limit swinging movement of the lever under the influence of the spring.

JOSEPH ANTHONY SEGALINI.
